UNITED STATES PATENT OFFICE.

JAMES H. NEAL, OF BOSTON, MASSACHUSETTS, ASSIGNOR OF ONE-HALF TO
FRANKLIN E. HUNTRESS, OF SOMERVILLE, MASSACHUSETTS.

BRAKE MECHANISM FOR RAILWAY-CARS.

SPECIFICATION forming part of Letters Patent No. 632,319, dated September 5, 1899.

Application filed January 13, 1899. Serial No. 702,018. (No model.)

To all whom it may concern:

Be it known that I, JAMES H. NEAL, residing in Boston, in the county of Suffolk and State of Massachusetts, have invented an Improvement 5 in Brake Mechanism for Railway-Cars, of which the following description, in connection with the accompanying drawings, is a specification, like letters and numerals on the drawings representing like parts.

10 This invention relates to a brake-operating mechanism especially designed and adapted for use on cars, either surface or elevated.

My present invention has for its object to provide cars propelled by motive power—such 15 as electricity, cable, compressed air, &c.—with a brake mechanism operated by power obtained from the moving car, but which is controlled by the motorman or operator on the car and preferably controlled by a hand-operated brake mechanism which is available 20 for use in case of accident to or derangement of the power-brake.

In the present embodiment of my invention the car carries a brake-cylinder provided 25 with a piston having its rod operatively connected to the car-brakes, which latter may be of any usual or suitable construction. The piston in the brake-cylinder is adapted to be actuated to set the brakes by a pump driven 30 from the car-axle and controlled by the motorman in a manner as will be described, and which pump when the car is in motion under normal conditions is driven from the car-axle and is inactive upon the piston; but 35 when it is desired to stop the car the pump is rendered active or effective on the said piston to set the brakes. The piston is also adapted 40 to be operated by the motorman in case of accident to the power-pump, whereby the brakes may be set by hand.

In accordance with this invention I employ oil or other liquid, which is adapted to be forced by the power-pump into the brake-cylinder and under proper conditions to move 45 the piston and set the brakes, and which oil is rendered ineffective on said piston to move the same when the car is in motion under normal conditions.

The action of the oil or other liquid upon 50 the piston in the brake-cylinder may and preferably will be governed by a valve, which is

controlled by a hand-operated brake mechanism carried by the car, and which latter may be of ordinary construction, or which may be of a novel construction, as will be described. 55

The power-brake mechanism may be controlled by an emergency device, as will be described.

These and other features of this invention 60 will be pointed out in the claims at the end of this specification.

Figure 1 is a side elevation of a sufficient portion of a railway-car provided with a brake mechanism embodying this invention to enable it to be understood; Fig. 2, a detail in plan of the car-truck and brake mechanism shown in Fig. 1, the car-body being omitted; Figs. 3 and 4, enlarged sectional details of the pump shown in Fig. 1; Fig. 5, a longitudinal sectional detail, on an enlarged scale, of the brake-cylinder shown in Fig. 1; Fig. 6, a sectional detail of the brake-cylinder on the line 6 6, Fig. 5, with the piston and valve omitted; Fig. 7, a vertical sectional detail on the line 7 7, Fig. 1, to be referred to; Fig. 7^a, a cross-section on the line 7^a 7^a, Fig. 7; and Fig. 8, a modification to be referred to. 70 75

In the present instance I have shown my invention as applied to a railway-car comprising a car-body A, mounted upon a four-wheel truck A', provided with wheels a a', mounted on axles a² a³; but instead of the particular form of car herein shown I may apply the invention to any other form such 85 as now commonly used on electric railways.

The car herein shown is provided with a brake-operating mechanism comprising a brake-cylinder a⁵, provided with a piston a⁶, having a rod a⁷ extended through one end of the said cylinder and connected, as herein shown, (see Fig. 2,) by a rod or link a⁸ to one end of a brake-lever a⁹, pivoted at a¹⁰ to an arm a¹⁴, fastened to a cross-beam a¹³, which is suitably secured to or supported from a stationary portion of the truck and shown as suspended by rods 10 from a cross-beam 12, fastened to the sides of the truck A', the brake-lever a⁹ being connected by an arm or bar a¹² to the brake-beam a¹⁵, carrying the brake-shoes a¹⁶, which co-operate with the wheels a. 90 95 100

The brake-cylinder a⁵ in the present in-

stance is flexibly suspended from the car-body, as by links a^{18} , and is provided with a lug or ear a^{19} , connected by link a^{20} with the brake-lever a^{21} , pivoted at a^{22} and connected to the brake-beam a^{23} , carrying the brake-shoes a^{24} , which coöperate with the wheels a' . The piston a^6 is designed in the present instance to be moved so as to apply the brake-shoes $a^{16} a^{24}$ both by power created by the revolution of a car-axle and by power created by hand-operated brake-handles $a^{25} a^{26}$ on upright rods or brake-staffs $a^{27} a^{28}$, carried by the dashers $a^{29} a^{30}$, after the manner now commonly practiced on electric-railway cars.

15 The piston a^6 may be operated by power by means of a pump, which is shown in the present instance as mounted on the axle a^2 and which consists of a casing b , provided with a chamber b' , in which are located eccentrics b^2 20 b^3 , set substantially opposite on said axle and having pivotally connected to their straps b^4 b^5 plungers $b^6 b^7$, reciprocating in cylindrical passages $b^8 b^9$, connected by branch pipes b^{10} b^{12} to a common outlet-pipe b^{13} , which leads 25 to a liquid-inlet pipe b^{14} for the brake-cylinder, the said inlet-pipe leading into the said cylinder behind the piston therein. (See Fig. 5.) The pipes $b^{10} b^{12}$ are provided with check-valves 15 16, (indicated by dotted lines, Figs. 3 and 4,) and which may be of any suitable or desired construction. The plungers $b^6 b^7$ are 30 suitably guided in the passages $b^8 b^9$, as by fingers b^{15} , attached to them. The pump-casing b is provided with a liquid-inlet pipe b^{16} , 35 connected in the present instance by a flexible pipe b^{17} to a pipe b^{18} , extended into a port or opening b^{20} in the bottom of the brake-cylinder and located, as shown, near one end of the same, the port b^{20} being larger than the 40 pipe b^{18} . The brake-cylinder a^5 in the present instance is inclosed by a casing b^{21} of materially larger diameter to form a chamber b^{22} to contain oil or other liquid supplied thereto through an inlet-pipe 20, and which chamber is adapted to be connected to the pipe b^{18} 45 under certain conditions, as will be described.

The brake-cylinder a^5 may be of any suitable or usual construction, and, as represented in Figs. 5 and 8, one end is removable, and 50 the inclosing case is made with one of its ends removable. The brake-cylinder a^5 , as shown in Fig. 5, is provided within it with a hollow piston-valve b^{25} , having reëntrant portions 2 3 on opposite sides of a circular portion 4, 55 constituting the valve proper, by which communication may be cut off between the oil-chamber b^{22} and the pipe b^{18} , the lower portion of the hollow valve having extensions or flanges 5 6 to prevent the passage of oil from 60 the brake-cylinder into the pipe b^{18} or oil-chamber b^{22} through the port b^{20} .

The piston-valve b^{25} may be provided with a hollow cylindrical stem or extension b^{30} , having attached to it a lug or projection b^{31} , 65 which coöperates with a port b^{32} in the cylinder a^5 and is provided with an extension which

leads into the upper portion of the oil-chamber b^{22} .

The piston-valve b^{25} fits the brake-cylinder substantially liquid-tight and coöperates with the piston a^6 to form in the brake-cylinder a chamber b^{35} , which is filled with oil or other liquid forced into said chamber by the pump when the brakes are set, as will be described.

The piston-rod a^7 is extended through the piston-valve b^{25} and its hollow stem b^{30} and through a stuffing-box b^{40} , and the said rod, as shown, is encircled by a spiral spring b^4 , having one end fastened to the stem or extension b^{30} and its other end fastened to the end of the brake-cylinder, the purpose of which spring will be hereinafter more fully described. The piston-valve b^{25} may and preferably will be moved in the brake-cylinder in the direction indicated by arrow 200, 85 Fig. 5, to close the port b^{32} by means of oil or other incompressible fluid b^{50} , which is forced into the brake-cylinder a^5 , behind the piston-valve b^{25} , through an inlet-pipe b^{51} , connected by a pipe b^{52} to the lower end of a substantially vertical cylinder b^{53} , attached to the car-platform b^{44} , the inlet-pipe b^{51} being also connected by pipe b^{54} to a like cylinder b^{55} , attached to the other platform b^{46} . The cylinders $b^{53} b^{55}$ are each provided with a plunger 95 or piston c , (see Fig. 6,) having a threaded socket in which fits the threaded end of the brake staff or rod coöperating with it, and said threads are made of steep pitch, as shown in Fig. 7, so that the plunger may be moved 100 upward in its cylinder by the pressure of the liquid contained therein.

By means of the threaded arrangement of brake-staff and plunger a rotary movement of the brake-staff in one direction produces 105 longitudinal movement of the plunger down in its cylinder without a corresponding longitudinal movement of the brake-staff, thereby forcing the oil or liquid in said cylinder and the pipe b^{52} , connecting it to the inlet-pipe b^{51} 110 of the brake-cylinder, into said brake-cylinder behind the piston-valve, thereby moving said valve in the direction indicated by arrow 200 in Fig. 5. The plunger c is held from 115 rotating in its cylinder in any desired or suitable manner which will not affect the reciprocation of the same, and which may be accomplished by means of a pin 300, extended through the cylinder into a longitudinal slot 301 in the plunger c . (See Fig. 7a.) The piston-valve b^{25} may thus be moved sufficiently 120 to apply the brakes by the power exerted by hand, the piston-valve in its movement carrying forward with it the liquid in the chamber b^{35} of the brake-cylinder and also the piston a^6 . The piston-valve b^{25} in its forward movement closes the outlet-port b^{32} for the oil-chamber within the brake-cylinder and at the same time uncovers the pipe b^{18} , and by the 125 reëntrant portion 2 connects said pipe with the chamber b^{22} , so that oil is drawn by the power-pump from the chamber b^{22} through the 130

reentrant portion 2 into the inlet-pipe b^{16} for the pump and is forced by the said pump into the brake-cylinder through the pipe b^{14} , thus moving the piston a^6 , so as to apply the brakes by power. The liquid forced by the pump into the brake-cylinder exerts pressure upon the piston a^6 to apply the brakes, and also exerts a back pressure upon the valve b^{25} ; but this back pressure is resisted by the power applied to the brake-staff, as a^{27} , which may be held by the motorman or by the usual pawl or dog now commonly employed on electric-railway cars, and which is pivoted on the car-platform and engaged with and disengaged from a ratchet-wheel fast on the brake-staff by the foot of the operator. If the pawl or dog is engaged with the ratchet-wheel, the brake-staff becomes stationary, and the plunger c is thereby rendered stationary and forms a solid abutment, by which the back pressure upon the valve b^{25} is resisted. The foot-dog and ratchet-wheel are not herein shown, as their use is well understood. To release the brakes, the operator releases the brake-staff and the back pressure of the oil in the brake-cylinder moves the valve b^{25} in the direction opposite to that indicated by arrow 200, Fig. 5, which forces the oil in front of it out of the brake-cylinder and into the cylinder b^{53} and moves the plunger upward in said cylinder, which upward movement of the plunger effects rotation of the brake-staff without corresponding vertical movement thereof. The release of the brake-staff relieves the pressure upon the piston a^6 sufficient to permit the brake-releasing springs c^5 , of any usual construction, to move the piston a^6 back into its normal position, (shown in Fig. 4,) and this return movement of the piston by the springs c^5 acts to create a pressure of the oil on the valve b^{25} to force the plunger upward in its cylinder. When the piston-valve is in its normal position, with the valve proper covering the port b^{20} and pipe b^{18} , and the car is again started, the pump is set in motion and the oil in the pipe b^{17} will be drawn into the pump and forced into the brake-cylinder, but will have no effect on the piston a^6 , as the outlet port or passage b^{30} is at such time open, and while the car is in motion the pump after emptying the pipe b^{17} is performing practically no work, and hence can be driven at a high speed by the car when in rapid motion without danger of setting the brakes.

From the above description it will be seen that the brakes may be applied by hand in case any accident should occur to the pump or its connections with the brake-cylinder, for by inspection of Fig. 5 it will be seen that a slight movement of the piston-valve brings its extension b^{30} into contact with the brake-piston a^6 and further movement of the piston-valve acts to set the brakes. Provision is also herein made for operating the power-brake in case of accident to the hand-operated brake—as, for instance, by leakage of oil from the cylinder b^{53} . In this case the oil is with-

drawn from behind the piston-valve b^{25} and the latter is moved by the spring b^{41} in the direction opposite to that indicated by the arrow 200 until the flange 6 on said valve strikes the end of the brake-cylinder, and at such time the reentrant portion 3 connects the pipe b^{18} with the oil-chamber b^{22} and the port b^{32} is closed by the valve b^{31} . The pump at such time takes oil from the chamber b^{22} and forces it into the brake-cylinder, and thereby applies the brakes. It will be noticed that the brake-cylinder is not rigidly secured to the car-body or to the car-truck, but is supported flexibly, so that the said cylinder moves when its piston is moved, but in an opposite direction thereto, to thereby apply one set of brakes, as a^{24} , the other set a^{16} being applied by the piston a^6 . By making the brake-cylinder movable to apply one set of brakes I am enabled to simplify the operating parts for said brakes, and while I prefer this arrangement it is evident that both sets of brakes may be operated by movement of the piston alone.

I have herein described the pump as performing practically no work when the car is running under normal conditions, and, while I prefer this arrangement, if desired the apparatus may be arranged so that the pump would circulate oil through the brake-cylinder without affecting the brakes until it was desired to apply the same. One arrangement by which this may be effected is shown in Fig. 8, wherein the brake-cylinder a^5 is connected with the chamber b^{22} through the port b^{32} and the pipe b^{18} communicates with the said chamber. With the arrangement shown in Fig. 8 the pump takes oil from the chamber b^{22} by the pipe b^{18} and forces it into the brake-cylinder through the pipe b^{14} and the oil passes out of the brake-cylinder into the chamber b^{22} through the port b^{32} . The pipes b^{52} b^{54} may be provided with shut-off valves d d' on opposite sides of the pipe b^{51} , so that in case the emergency-valve b^{31} is operated by leakage from either cylinder b^{53} b^{55} said cylinder may be cut off and the oil in the other cylinder employed to restore the piston-valve to its normal condition and also to operate said valve, as above described.

The brake-staffs may be held from rotating in the reverse direction under the influence of the back pressure of the liquid on the piston c either by the motorman or by a dog or pawl, (not herein shown,) but which is located on the car-platform and engages a ratchet-wheel fast on the brake-staff after the manner now commonly employed on electric-railway cars.

From the above description it will be seen that the car may be stopped in its motion by applying the brakes in the following ways—namely, first, by moving the brake-handle sufficient to close the port b^{32} and enable the pump to set the brakes; second, by continuing the movement of the brake-handle sufficient to set the brakes without regard to the

power-pump or in combination with the same, and, third, by closing the port b^{32} by the emergency-valve.

The oil may be supplied to the system 5 through a pipe 50, (see Fig. 5,) connected to the pipe b^{51} , and the air in the system may be vented through a pipe 51.

I claim—

1. The combination of the following instrumentalities, viz: a railway-car, brake mechanisms therefor, a brake-cylinder provided with a piston having its rod connected to one of said brake mechanisms, a liquid-pump driven from an axle of the car and connected to said 15 brake-cylinder to force liquid into said cylinder while the car is in motion under normal conditions without setting the brakes, a valve in said brake-cylinder to control the passage of liquid out of said cylinder, and means to 20 operate said valve, substantially as described.

2. The combination of the following instrumentalities, viz: a railway-car, brake mechanisms therefor, a brake-cylinder provided with a piston having its rod connected to one of 25 said brake mechanisms, a liquid-pump provided with a piston positively driven from an axle of the car and connected to said brake-cylinder to force liquid into said cylinder while the car is in motion under normal 30 conditions without setting the brakes, a valve in said brake-cylinder to control the passage of liquid out of said cylinder, and a hand-operated mechanism operative upon said valve to close the liquid-outlet from the said cylinder 35 and thereby apply the brakes, substantially as described.

3. A brake-operating mechanism for railway-cars comprising a brake-cylinder provided with a piston operatively connected to 40 the car-brakes, and a liquid-pump operated from a car-axle to force liquid into the brake-cylinder to move said piston and apply the brakes, a valve normally rendering the operation of the pump ineffective upon said piston 45 ton, a cylinder provided with a piston and containing liquid, a pipe connection between said cylinder and valve, and a hand-operated device to move said piston in its cylinder in one direction and thereby cause the 50 liquid contained therein to act on said valve to render the operation of the pump effective upon the piston of the brake-cylinder, substantially as described.

4. The combination with a railway-car, of a power-brake-operating mechanism comprising 55 a pump actuated from an axle of the car, a brake-cylinder connected to said pump, and having its piston connected with the brake mechanism of said car, manually-operated mechanism controlling the effective operation of the pump upon the piston in said 60 brake-cylinder and effective upon the brake mechanism to apply the brakes independent of the said pump, substantially as described.

5. The combination with a railway-car, of a 65 power-brake-operating mechanism actuated from an axle of the car, and normally inoperative while the car is in motion, manually-operated mechanism controlling the effective 70 operation of the power-brake mechanism, and means to render said power-brake operative in case of accident to said manually-operated mechanism, said means being normally inactive, substantially as described.

6. The combination with a railway-car, of a 75 power-brake mechanism comprising a brake-cylinder provided with a piston operatively connected to the car-brakes, a liquid-pump operated from an axle of said car and connected to said brake-cylinder; a valve in said 80 brake-cylinder controlling the action of the said pump upon said piston, and means to operate said valve, substantially as described.

7. The combination with a railway-car, of a power-brake mechanism comprising a brake-cylinder provided with a piston operatively 85 connected to the car-brakes, a liquid-pump operated from an axle of said car and connected to said cylinder to force liquid therein, a valve in said brake-cylinder controlling the 90 action of said pump to render the fluid in the cylinder effective upon the said piston, means to operate said valves, a second valve to control the action of the pump on said piston, and means to operate said second valve to 95 render the liquid forced into the brake-cylinder effective upon the piston to apply the brake, substantially as described.

In testimony whereof I have signed my name to this specification in the presence of 100 two subscribing witnesses.
